LUMBER FEEDING AND MANIPULATING MEANS

Original Filed March 26, 1923

Patented Oct. 23, 1928.

1,688,416

UNITED STATES PATENT OFFICE.

LEO J. GRUBMAN, OF BELLE HARBOR, AND EDWIN A. GODLEY, OF NEW YORK, N. Y.

LUMBER FEEDING AND MANIPULATING MEANS.

Original application filed March 26, 1923, Serial No. 627,595. Divided and this application filed May 9, 1924. Serial No. 711,974.

This invention relates to lumber feeding and manipulating means and constitutes a division of our copending application for patent, Serial No. 627,595, filed March 26th, 1923, 5 on which U. S. Patent 1,652,198 has been issued.

It is the primary object of our present improvement to provide a lumber feeding and manipulating means whereby during the 10 feeding movement of the lumber or boards, a grading expert may inspect all parts of the boards without interruption of the feeding movement, and thus accurately determine the proper grade thereof.

15 In one practical embodiment of our invention, we provide a series of positively driven feed rollers, and means associated therewith to support the board on edge in a vertical plane during the first portion of 20 its feeding movement and then subsequently dispose the board in a horizontal plane for continued feeding movement by the roller. Thus both sides of the board will be exposed to view so that any imperfections therein may 25 be duly noted and the proper grade of the board determined accordingly.

It is a further general object of our invention to provide a lumber feeding means of the above character which is quite simple in its construction and therefore, strong and durable and which will relieve the grading expert of the necessity of manually manipulating or handling the individual boards.

With the above and other objects in view, 35 our invention consists in the improved lumber feeding and manipulating means, and in the form, construction and arrangement of the several parts thereof as will be herein-after more fully described, illustrated in the 40 accompanying drawings and subsequently incorporated in the subjoined claims.

In the drawings wherein we have disclosed one simple and satisfactory embodiment of the invention and in which similar reference characters designate corresponding parts 45 throughout the several views:

Figure 1 is a top plan view of an embodiment of our improved lumber feeding and manipulating means; and

50 Figure 2 is a longitudinal section taken on the line 2—2 of Figure 1.

In the accompanying drawings we have shown the lumber feeding means which constitutes the particular subject matter of this 55 application associated with an automatic

grade marking or stamping mechanism and an automatic measuring mechanism. These grade stamping and measuring mechanisms are fully illustrated, described and claimed in our original application above referred to. Therefore, for the purposes of this explanation it will suffice to state the boards are successively fed without interruption of their movement by the feeding unit. A first to the grade marking or stamping mechanism B, and then to the measuring mechanism C. However, it will be understood that in so far as the novel features of the board feeding and manipulating means herein claimed is concerned, such means might be advantageously used independently of the grade stamping and measuring mechanism.

In the embodiment of the invention which we have selected for purposes of illustration, the feed table consists of similar parallel side 75 frame members 5 in which a plurality of spaced parallel transversely positioned rollers 6 are suitably journaled at their ends. The roller shafts at one of their ends, are extended beyond the frame member 5 and 80 provided with suitable sprockets for engagement by the drive chain 7. Rotation is imparted to one of the end rollers through a suitable driving connection 8 from any convenient source of power, and through the 85 medium of the chain 7 the remaining rollers are positively driven or rotated in the same direction and at the same speed.

Upon one of the side frames 5 and spaced 90 above the same, a longitudinally extending guide rail 9 is suitably supported. This rail extends from one end of the table and terminates in an inwardly curved finger 10 at a point in spaced relation to the opposite end of the table. Those feed rollers 6 for 95 the longitudinal extent of the rail 9 are provided at one of their ends and adjacent to the inner side of said rail with the circumferential grooves 11. The lumber or board, as indicated at L in Figure 2, is placed upon the feeding rollers in edgewise position with the lower longitudinal edge of the board engaged in the grooves 11. As these rollers rotate, the board is longitudinally fed with its outer side in contact with the rail 9. 100 As the end of the board strikes the inwardly curved finger 10 of said rail, the board is turned inwardly so that it falls downwardly to a horizontal position upon the feed rollers 6, the feeding movement being then con- 110

tinued with the board in this position. It will thus be apparent that a grading expert stationed at one side of the feed table will first observe one side of the board as it is moved longitudinally by the feed rollers in the position seen in Figure 2, and then when the board is disposed in a horizontal position on the rollers as above explained, he can readily observe the opposite side thereof. Thus the board can be carefully inspected, its imperfections noted and its proper grade determined accordingly.

From the foregoing description, the construction and manner of operation of our present improvement will be clearly and fully understood. It will be seen that no manual handling or manipulation whatever of the board is required, while at the same time all surfaces of the board are fully exposed to inspection by the grading expert stationed at one side of the table so that he may properly determine the particular grade of the individual boards as they are continuously moved by the feeding rollers to the grade marking mechanism, or to a planer or other machine. Thus the possibility of errors in determining the various grades and marking the boards accordingly is reduced to a minimum.

In the drawings and the foregoing description, we have disclosed an embodiment of our invention which we believe to be thoroughly practical for the purpose in view, but it is nevertheless apparent that other alternative embodiments of such board feeding and manipulating means might be devised for the purpose of obtaining similar results. Accordingly, it is to be understood that we reserve the privilege of adopting all such modifications in the construction, relative proportions and arrangement of the several elements as may be fairly embodied within the spirit and scope of the invention as claimed.

We claim:

1. In combination with a lumber feeding table having a plurality of spaced feed rollers provided adjacent one of their ends with circumferential grooves, a fixed guide rail extending longitudinally above said grooved ends of the rollers and adapted to sustain a board in a substantially vertical position with its lower edge engaged in the grooves of said rollers, means for rotating said rollers to feed the board longitudinally along said rail, and said rail provided with means at one of its ends against which the board is directed and whereby the board is moved from such vertical position to a substantially horizontal position upon the feed rollers of the table.

2. In combination with a lumber feeding table, means for mechanically manipulating each piece of lumber during its movement over the table, said means including a member to sustain the lumber in one position for a portion of its movement, said member

having means to coact with the lumber as it is fed forwardly over the table and dispose the lumber in another position during the remainder of its feeding movement whereby both sides of the lumber are exposed for inspection.

3. In combination with a lumber feeding table, a longitudinally extending rail supporting the lumber in one position during the first part of its feeding movement, said rail terminating at one of its ends in means adapted to coact with each piece of lumber as it is fed forwardly over the table to automatically dispose the same in another position and at right angles with respect to its first position for the remainder of the feeding movement to thereby expose both sides of the lumber for inspection.

4. In combination with a lumber feeding table including a plurality of feed rollers, certain of said rollers having circumferential grooves to receive one longitudinal edge of the board and support the same in a vertical plane during the first part of its feeding movement, relatively stationary means having a part adapted to coact with one end of the board and automatically cause the same to move to a horizontal position upon the feed rollers to thereby dispose both sides of the board for inspection.

5. In combination with a lumber feeding table including a plurality of feed rollers, certain of said rollers having circumferential grooves to receive one longitudinal edge of the board and support the same in a vertical plane during the first part of its feeding movement, a stationary cam member mounted above the table at one end of the grooved series of rollers with which the end of the board is adapted to engage, whereby the board is moved from its vertical position to a horizontal position upon the feeding rollers to expose both sides of the board for inspection.

6. In combination with a lumber feeding table having a plurality of spaced feed rollers and operating means therefor, a fixed rail extending longitudinally along one side of the table above the rollers to sustain a board in vertical position for a part of its travel over the table, said rail at one of its ends terminating in an inwardly extending cam portion with which one end of the board is adapted to coact whereby the board is caused to move from such vertical position to a horizontal position upon the feed rollers to thereby expose both sides of the board for inspection.

7. In combination with a lumber feeding table having a plurality of spaced feed rollers and operating means therefor, certain of said rollers having circumferential grooves adjacent one of their ends, a fixed longitudinally extending rail mounted above the grooved ends of the latter rollers and sustaining the board in a vertical position with its lower

edge engaged in said grooves during the first part of the feeding movement of the board, said rail at one end having an inwardly curved cam portion with which the end of the board is adapted to be engaged, whereby the board is caused to move from such vertical position to a horizontal position upon the feed rollers to thereby expose both sides of the board for inspection.

- 10 8. In combination with means for feeding a board arranged on edge in the direction of its length comprising means above said feeding means and caused by the movement of the board to move the said board from a position in a vertical plane to a position in a horizontal plane, whereby both sides of the board are exposed for inspection without interruption of the feeding movement of said board.
- 15 9. In a lumber feeding mechanism com-

prising means for supporting and conveying a board in a vertical plane, and means independent of the conveying means and caused by the movement of the board to automatically dispose said board in a horizontal plane 25 without interruption of the continued feeding movement of the board.

10. In combination with a plurality of spaced feeding rollers, means for supporting a board on edge in a vertical plane on said rollers, and means above the rollers for moving the board to a horizontal position upon said rollers caused by the movement of the board on the rollers.

In testimony that we claim the foregoing 35 as our invention, we have signed our names hereto.

LEO J. GRUBMAN.
EDWIN A. GODLEY.
